FLUID FLOW PULSATION DAMPING

Sheldon E. Isakoff, Wilmington, Del., assignor to E. I. du Pont de Nemours and Company, Wilmington, Del., a corporation of Delaware

Application August 13, 1953, Serial No. 373,969

2 Claims. (Cl. 230—236)

This invention relates to means for damping or reducing the flow and pressure pulsations in gas streams, such as those that exist at the suction and discharge points of reciprocating compressors, blowers, internal combustion engines, and the like.

Numerous means and methods are known commercially for damping pulsations, but in most part are suitable only for certain conditions for which they were specifically designed or applied, and are ineffective, uneconomical, or inapplicable generally to widely varying conditions such as are encountered in high-pressure chemical operations.

Major advantages that are at once apparent from the present invention as applied in actual operations include increased pulsation reduction and simplicity of construction, and particularly the ability by this means of predicting the degree of pulsation reductions where conditions and the nature and characteristics of the gas or fluid to be handled are widely variant. Also, there is an economic advantage in achieving pulsation reduction.

The performance of a unit constructed in accordance with the present invention can be predicted from the known physical properties of the gas or fluid, and can be substantially accurately determined regardless of the size, pressure, temperature or source of pulsations.

Also detrimental effects of pulsations in a fluid flow system, which may be avoided by means of this invention, include (1) excessive mechanical vibration, resulting in unsafe conditions and fatigue failures; (2) excessive pressure stresses; (3) difficult process control; (4) variable heat- and mass-transfer rates; and (5) reduced compressor or pump efficiency.

It has been determined that when the single means provided by this invention is included in the fluid or gas stream, pressure and flow fluctuations are at once sharply reduced. One theoretical feature of the present invention comprises applying the principles of wave interference, by operating the components of the wave train in the gas stream in such a manner that they tend to cancel each other and to impede the transmission of the pulsations.

The invention also embodies the principle of a low-pass filter, the effectiveness of which is increased to a maximum by maintaining the cut-off frequency lower than the frequency of pulsation that is desired to be eliminated.

A specific embodiment of the present invention comprises a system of three tanks or compartments interconnected by a relatively restricted flow-passage through which the fluid or gas passes. With the size and arrangement of the tanks and interconnecting passage assembled in conformity with the principles and formulae fully discussed hereinafter, it will at once be apparent that much greater pulsation reduction is attained than can be produced with prior known single tank, or even two-compartment tanks having the same total volume and entailing approximately the same pressure drop. In a preferred embodiment of the invention three compartments are

2

provided and contained all in a single tank or shell, which at the same time houses the interconnecting pipe communicating with each of the compartments.

It will be understood that other embodiments will become apparent from the foregoing that may fall within the broad principles of the invention herein set forth and disclosed.

It is to be understood that the specific form of this invention as it may be applied in any given circumstance may depend upon the source of the pulsations where they occur, flow characteristics, and space requirements.

An essential feature of the invention however is that the compartments and interconnecting or intercommunicating pipes are sized and arranged in conformance with the principles and formulae discussed in detail herein below.

The nature of the invention will be more fully understood from the following detailed description and by reference to the accompanying drawing in which like reference characters represent like or similar parts and

in which:

Fig. 1 is a longitudinal, sectional view of one embodiment of a unit constructed in accordance with the present invention, and

Fig. 2 is a view similar to Fig. 1 but showing a modified form of intercommunicating pipes;

Fig. 3 is a cross-section through another embodiment, while Fig. 4 represents a still further embodiment, and

Fig. 5 is a graphic illustration of the performance of a unit constructed in accordance with this invention.

In Fig. 1, A designates the source of pulsating flow, which in the broad aspects of the invention may be any one of different gas moving units imparting pulsations to a fluid stream in pipe B. The fluid pulsation sources may include any of the usual piston-type compressors employed in gas compressor or chemical plants. Such compressors may be single or multi-cylinder and may be single or double acting. A given compressor will produce pulsations in the passage connected to it at a rate corresponding to the number of gas discharges per unit time. The fundamental frequency of pulsation F in cycles per second is given by:

$$(1) \quad F = n_1 \frac{(\text{R. P. M.})}{60}$$

where n_1 is the number of cylinders for a single-acting machine or twice the number of cylinders for a double-acting compressor. The gas is discharged by the compressor through the pulsation damper when the pulsations are to be reduced on the discharge side of the prime mover. If the pulsations are to be removed on the inlet side of the prime mover, the apparatus should be located on that side. It will be understood also that the exact location of the pulsation damper will depend on the purpose for its operation, space requirements, and other convenience factors.

As shown in Fig. 1, the damper comprises a single shell, C, with two transverse partitions, D and E, dividing the shell into three chambers or zones, F, G, and H. The chambers or zones provide capacitance where gas rushing in is compressed and stored for short periods of time. Gas enters the unit at I and discharges at J. These inlet and discharge points merely represent connections to and from chambers F and H, and are not necessarily required to be in line as shown. Since the construction is substantially symmetrical, the direction of gas flow through the device is immaterial. As shown, the shell contains a pipe K interconnecting the three chambers or zones. The mass of gas in the pipe K possesses inertia and resists a change in its rate of flow; pipe K therefore represents an inductive passage. Chamber or zone G is fully closed except for the opening into the interconnecting pipe L, which pipe also

constitutes an inductive passage. The pipe L opening to chamber or zone G is connected as shown substantially at the midpoint of pipe K. Gas therefore moves in and out of this chamber as with a side-branched surge tank. The volumes of the chambers and the length and diameter of the interconnecting pipe are predetermined in a manner explained more fully hereinafter. The pipe K is preferably welded to and supported by the shell and transverse partitions. Liquid which may separate out in the apparatus is removed from the chambers through the drain plugs M, N, and O.

While the intermediate chamber or zone may be of substantially the same capacity as the inlet and outlet chambers or zones, the volume or capacity of the central or intermediate chamber or zone may vary between 15 60% and 160% of the volume or capacity of the inlet and outlet chambers or zones.

The interconnecting pipe may be longer than the length of the shell, in which case it may be coiled inside the chamber volume as shown in Fig. 2.

While good results in pulsation damping will be produced by applying the general configuration illustrated and described in the foregoing, and variations and modifications within the scope of this invention will become apparent from the full disclosure herein, it is to be understood that optimum results will be obtained by following the procedures given below.

A. Method of determining size of chambers and interconnecting pipe

1. Determine the lowest frequency of pulsation which one desires to eliminate. As described earlier, when the source of pulsation is a reciprocating compressor, this frequency is given by Equation 1. All harmonics of this fundamental frequency will be higher than this, of course. Where the source of pulsation is a rotary blower, the lowest frequency of pulsation is given by

$$(2) \quad F = \frac{R.P.M.}{n_2 \cdot 60}$$

where n_2 is the number of blower blades.

2. Select the cut-off frequency, f_c , of the pulsation damper at 80-90% of F. (NOTE.—The smaller the ratio

$$\frac{f_c}{F}$$

the more conservative will be the design. Values of f_c/F greater than 1.0 will not give as high a degree of pulsation damping as below 1.0.)

3. Determine the volume of the chambers and the lengths and diameters of the internal passage by the following relationship:

$$(3) \quad \frac{L_1 V}{d_1^2 (1+p)} = \frac{.0398 c^2}{f_c^2}$$

where:

V =volume of chambers F and H, cu. ft.

L_1 =length of interconnecting pipe from x to y , ft.

d_1 =diameter of interconnecting pipe between x and y , ft.

c =velocity of sound in gas, ft./sec.

p =a numerical factor which can be set between 0.3 and 0.08, preferably 0.45 to 0.65.

The velocity of sound in the gas may be approximated from tables, and corrected for the temperature and pressure conditions which exist in the line where pulsations are to be reduced, or determined from the thermodynamic properties of the gas. (A discussion on the computation of the velocity of sound in a gas is given in various sources, including "Vibration and Sound," by P. M. Morse, 2nd edition, pp. 217-221, 1948.)

The right hand side of Equation 3, involving the cut-off frequency and the properties of the gas, has now been specified, and a numerical value can be computed.

Consider now the left side of Equation 3. The numerical value of p is set first. A value of 0.55 is usually convenient and leads to highly effective de-

signs. Effective and economical pulsation damping can also be obtained with values of p ranging between 0.3 and 0.8, however.

Next, either the volume, V , of the inlet (and exit) chamber is specified, or the ratio

$$\frac{L_1}{d_1^2}$$

is set, depending upon whether the allowable pulsation damper volume or the fluid flow pressure loss through the unit is considered to be the limiting factor. In high pressure applications, the cost of heavy-walled vessels may determine or govern the design to be based on a minimum volume basis, while considerable pressure loss may be allowable. On the other hand, at low pressures, material cost might be a relatively small percentage of the total installation cost, but pressure drop can well be the critical factor.

(a) If total volume is the limiting factor, the design would proceed as follows: Set the volume, V , equal to approximately 20-30 times the volume of a single flow pulse from the prime mover. That is, the volume V , is given by:

$$25 \quad V = \frac{Q}{F} \times 25 \quad (4)$$

Where Q equals the average flow rate in cubic feet per second, and F is the fundamental pulsation frequency in cycles per second. Where the pressure of a gas being handled is high enough to reduce its compressibility (increase the velocity of sound in the gas), the above multiplication factor should be increased to compensate for the reduction. That is, if the gas compressibility is reduced by a factor of two, then Formula 4 should read

$$V = \frac{Q}{F} \times 25 \times 2$$

This is to prevent excessive pressure pulsations being reflected back to the prime mover. With V specified, the ratio

$$\frac{L_1}{d_1^2}$$

is established. The length and diameter are then chosen for convenience. For the design formulae to be accurate, it is important to keep the length of the interconnecting pipe below $1/2$ wave length of sound in the gas. Experience indicates that in the gas handling field, the length of the interconnecting pipe need seldom exceed $1/6$ of the fundamental wave length.

(b) Where the pressure drop is the limiting factor, the ratio

$$\frac{L_1}{d_1^2}$$

is arbitrarily set at as large a value as can be tolerated with regard to the pressure loss. Pressure drop through the chambers and interconnecting pipe is computed in the usual manner, based on the average gas flow rate through the unit. In setting the values of L_1 and d_1 , a convenient starting point is to set the value of d_1 . The pressure drop through the unit is approximately equal to

$$\left(1.5 + \frac{L_1}{d_1} \right)$$

velocity heads ("Using the velocity head concept in pressure drop calculations," C. E. Lapple, Heating, Piping and Air Conditioning, vol. 17, pp. 179-83, 262-67, 319-24, 1945) based upon the velocity in the interconnecting pipe. (Now, the value of V can be determined since all other terms in Equation 3 have previously been determined.)

(c) Where neither total volume or pressure drop are specified, an effective, economical unit can usually be designed by starting with the interconnecting pipe and

setting its diameter equal to approximately $\frac{1}{3}$ of the pipe line diameter.

4. It remains only to determine the volume of the center chamber, and the length and diameter of the passage leading from point Z and connecting to chamber G.

The volume of G should be set equal to $2pV$. Since p and V have already been determined, the volume of chamber G can be computed numerically. The length, L_2 , and diameter, d_2 , of the pipe L leading from point Z to chamber G is given by:

$$\frac{L_2}{d_2^2} = \frac{(1-p)(L_1)}{4p(d_1^2)} \quad (5)$$

It is generally simplest to use the same diameter for the pipe L as for the interconnecting passage K; in this case, Equation 5 becomes:

$$L_2 = \frac{(1-p)L_1}{4p} \quad (5)$$

Satisfactory performance will still be obtained for values of d_2 as low as $\frac{1}{6}$ of d_1 . If the ratio of d_2/d_1 is less than 0.2, the resistance to fluid motion of pipe L will be high, and the effectiveness of the capacitance chamber G will be decreased; d_2 could be made greater than d_1 , but this would not be economical, since the length L_2 would then have to be increased in order to obtain a specified numerical value of

$$\frac{L_2}{d_2^2}$$

15

required by Equation 5.

Although the degree of pulsation reduction that is achieved in practice by means of a single, three-compartment combination as illustrated herein will, in general, be entirely adequate, it will be apparent from the foregoing that even greater pulsation damping will be obtained by including or providing additional compartments with their associated interconnecting pipes designed in conformity with the preceding principles and formulae. The additional chambers and interconnecting pipes may be placed in the gas stream following the three-chamber unit, and again, for some purposes, all compartments and pipes may be placed in a single shell.

It should be understood that equivalent values for the inductive passages determined as specified above could be obtained by using two or more interconnecting pipes in parallel. The effective inductance of n pipes of equal length in parallel arrangement is equal to

$$\left(\frac{1}{n}\right)^{th}$$

30

of a single section of such pipe. Thus, if a number, n , of parallel inductive passages were used, the length of each passage would have to be n times that of the single passage specified in the preferred method of design above. Clearly, this is not economical, and has no apparent advantages over the single inductive passage.

It should further be understood that equivalent values for each of the capacitive chambers determined as specified above could be obtained by providing more than one compartment or tank in parallel arrangement. The effective capacitance of n chambers of equal volume in parallel arrangement is equal to n times the capacitance of a single such chamber. Thus, if a number, n , of parallel capacitance chambers were provided, the volume of each chamber would have to be

$$\left(\frac{1}{n}\right)$$

times that of the single chamber or compartment specified in the preferred method above. In general, it will be found more economical to provide or employ a single capacitive chamber.

It will be understood, and the claims are to be so

construed, that the stated equations express the theoretically correct relationships and values and that in practice it may not be necessary to adhere precisely thereto so long as the calculations or relative proportions of the apparatus conform fundamentally and substantially to the equations.

A further modification of the three-compartmented pulsation damper is illustrated in Figure 4 in which the corresponding center or intermediate compartment, G₁, comprises the annular space between the outer and inner shells C₁ and C, respectively, as shown, the remaining equivalent elements to those illustrated in Figures 1 to 3 being similarly designated.

B. Example

To further illustrate the method of design and practical application of the invention, the following example is selected from an actual installation.

Problem: To remove pulsations from a gas stream, 20 substantially ethylene, discharging from a double acting compressor into a 6-in. line. The minimum compressor operating speed is 250 R. P. M., maximum 300 R. P. M., and the maximum flow rate is 8,200 pounds per hour. Line pressure at the discharge is 425 p. s. i., temperature 25 100° C., density 1.81 lb./cu. ft., and the velocity of sound in the gas mixture at these conditions is 1150 ft./sec. It is further specified that space is limited and that the volume of damper should be kept to a minimum.

Solution: Minimum fundamental frequency

$$\frac{2 \times 250}{60} = 8.33 \text{ pulses/sec.}$$

$$\text{Maximum pulsation frequency} = \frac{300}{60} \times 2 = 10 \text{ pulses/sec.}$$

35 Volume per pulse = $\frac{8200}{3600 \times 1.81 \times 10} = 0.126 \text{ cu. ft.}$
Set the volume of the inlet chamber equal to 20 times 40 the volume of the flow pulse, and set the value of p equal to 0.55. Set f_c at 85% of minimum fundamental frequency.

45 Volume of inlet chamber = volume of exit chamber
= $20(0.126) = 2.52 \text{ cu. ft.}$
Volume of center chamber = $2(0.55)(2.52) = 278 \text{ cu. ft.}$
 $f_c = .85(8.33) = 7.08 \text{ cycles/sec.}$

From Equation 3

$$\frac{L_1}{d_1^2} = \frac{.0398(1150)^2(1+0.55)}{2.52(7.08)^2} = 646$$

50 From computation of the fluid pressure drop for the maximum gas flow rate, it was determined that an interconnecting pipe whose nominal inside diameter was 2 inches would be satisfactory. Thus, the length, L_1 , of the interconnecting pipe, K (or the distance xy), is:

$$L_1 = 646 \left(\frac{2.067}{12} \right)^2 = 19.2 \text{ ft.}$$

60 (Actual inside diameter of a 2-inch schedule 40 pipe is 2.067 in.) The length to the T in the interconnecting pipe, $xz = \frac{1}{2}(19.2) = 9.60 \text{ ft.}$ Using a 2-inch pipe also for the passage leading to the center chamber, G, the length L_2 or the distance zz' is given by Equation 6:

$$\frac{(1-0.55)(19.2)}{4(0.55)} = 3.92 \text{ ft.}$$

65 To further indicate the effectiveness of the invention, and the ability to accurately predict the performance of the system in actual operations, Figure 5 is presented. The curve represents the results of numerous tests on small scale models, indicating, as ordinate, the ratio of the pressure pulsation amplitudes after passing through this system to the pressure pulsation amplitudes which exist upstream of the equipment (at the pulsation source), as a function of the frequency of pulsations. That is,

Figure 5 presents a generalized plot of pressure pulsation transmission versus pulsation frequency performance of the invention, and can be applied to predict the performance of actual installations. Pulsation frequency is expressed as a fraction of the cut-off frequency of the pulsation damper. Recalling that in the design of embodiments of the invention, f_c is chosen at 80-90% of the lowest frequency of pulsation to be eliminated (F), it will be apparent that in any installation, operation will always be to the right of the dotted line, and pulsations will be substantially eliminated.

To indicate the remarkable effectiveness of the invention in damping fluid pulsations, measurements made before and after installation of the unit given in the example above will be given. Before installation, the maximum amplitude of pressure pulsations in the ethylene line was 40 p. s. i. or approximately 10% of the average line pressure. After installation, with the compressor operated at 275 R. P. M., the amplitude of pressure pulsations downstream of the damper was 1.0 p. s. i., a reduction to less than 0.25% of line pressure. In addition, the amplitude of pressure pulsations between the damper and the compressor was only 21.1 p. s. i. Installation of the damper thus achieved two desirable results: reduction of pulsation at the compressor discharge and substantially complete elimination of pulsation in the ethylene process line. The measured value of the pulsation transmission ratio was 0.047, whereas the predicted value of this ratio (Figure 5) was 0.030, thus indicating another advantage of the invention in that the results can be closely predicted.

I claim:

1. In combination with a gas compressor or blower, apparatus for dampening pulsations in a gas stream having pulsating flow delivered by said gas compressor or blower comprising separate gas entrance and gas exit chambers having relatively large capacitances, said gas entrance chamber communicating with said gas compressor or blower and said gas exit chamber communicating with a gas delivery line, a third capacitance chamber, and an inductive passage or conduit in open communication with said gas entrance and gas exit chambers, said inductive passage being provided with a branch passage of substantial inductance in open communication with said third capacitance chamber, the volumes of said chambers and the dimensions of said inductive passage

and said branch passage having predetermined values substantially in accordance with the following equations:

$$\frac{L_1 V}{d_1^2 (1+p)} = \frac{0.398 c^2}{f_c^2}$$

and

$$\frac{L_2}{d_2^2} = \frac{(1-p)L_1}{4p(d_1)^2}$$

where:

10 L_1 =length in feet of the inductive passage in open communication with said gas entrance and gas exit chambers,

d_1 =diameter in feet of said inductive passage,

V =volume in cubic feet of each of said gas entrance and exit chambers,

p =a numerical factor which can be assigned a value in the range 0.3-0.8, but preferably 0.45-0.65,

c =the velocity in ft./sec. of sound in the gas, and

f_c =a selected cut-off frequency in cycles/sec. above which pulsation dampening is desired and where

20 $2pV$ =volume in cubic feet of said third capacitance chamber,

L_2 =length in feet of said branch passage connecting said inductive passage with said third capacitance chamber, and

25 d_2 =diameter in feet of said branch passage connecting said inductive passage with said third capacitance chamber.

30 2. An apparatus according to claim 1 wherein f_c is of a preselected value below the lowest frequency of pulsation imparted to said gas stream by said compressor.
